US00D821403S

(12) **United States Design Patent** (10) Patent No.: **US D821,403 S**
Howell et al. (45) Date of Patent: ** Jun. 26, 2018

(54) **DOCUMENT READER**

(71) Applicant: **GEMALTO SA**, Meudon (FR)

(72) Inventors: **Brett A. Howell**, Ramsey, MN (US);
Chin-Yee Ng, Oakdale, MN (US); **John M. Pilgrim**, Woodbury, MN (US); **Lori A. Sjolund**, Stillwater, MN (US);
Glendon D. Kappel, Eagan, MN (US)

(73) Assignee: **GEMALTO SA**, Meudon (FR)

(**) Term: **15 Years**

(21) Appl. No.: **29/599,809**

(22) Filed: **Apr. 6, 2017**

(51) LOC (11) Cl. **14-02**

(52) U.S. Cl.

USPC **D14/424; D14/425**

CLAIM

The ornamental design for a document reader, as shown and described.

DESCRIPTION

FIG. 1 is a perspective view showing the new design for a document reader;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines shown represent unclaimed features of the document reader and form no part of the claimed design.

1 Claim, 4 Drawing Sheets
